UNITED STATES PATENT OFFICE.

JOHN HAYS HAMMOND, JR., AND HENRY L. F. BUSWELL, OF GLOUCESTER, MASSACHUSETTS; SAID BUSWELL ASSIGNOR TO SAID HAMMOND.

MIXTURE AND METHOD FOR PRODUCING SMOKE.

Application filed August 11, 1917, Serial No. 185,794. Renewed July 12, 1921. Serial No. 484,191.

To all whom it may concern:

Be it known that we, JOHN HAYS HAMMOND, Jr., a citizen of the United States, and a resident of Gloucester, in the county 5 of Essex, State of Massachusetts, and HENRY L. F. BUSWELL, a subject of the King of Great Britain, and resident of Gloucester, in the county of Essex and State of Massachusetts, have invented a certain new and 10 useful Mixture and Methods for Producing Smoke, of which the following is the specification.

Some of the objects of this invention are to provide a mixture of material which will 15 be effective in producing rapidly large volumes of dense smoke particularly for the purpose of producing smoke screens in warfare; to provide an improved process of producing quickly dense volumes of smoke; 20 and to provide other improvements as will appear hereinafter.

In the accompanying drawings, Fig. 1 is a diagrammatic side elevation in vertical section, of a smoke producer which may be 25 utilized in applying this invention; Fig. 2 is a symbolic representation of a mixture forming a part of this invention; and Fig. 3 is a symbolic representation of an improved process forming a part of this invention.

30 It is well known that in modern warfare it is frequently desirable to produce quickly large quantities of dense smoke, as for instance to provide smoke screens for concealing vessels or for concealing military operations from an enemy, and we have discovered 35 that a mixture of calcium carbonate ($CaCO_3$) and pitch when burned in a confined space and under the influence of a restricted or limited amount of air will produce quickly large volumes of dense smoke 40 which is particularly suitable for purposes of warfare.

In producing smoke from this mixture of calcium carbonate and pitch, any well known 45 smoke producer may be used, for instance such a smoke producer as is shown in Fig. 1 comprising a combustion chamber 10 having an outlet through a chimney or delivery pipe 11 and provided with a liquid fuel 50 burner 12, such for instance as a liquid fuel burner arranged to be provided with a fuel pipe 13 with liquid fuel from a tank 14. The combustion chamber may also be provided with a plurality of air inlets 15 arranged to be controlled by a reciprocatory

damper 16 provided with openings 17 arranged to register with the air inlets 15 when the damper 16 is in a suitable position. The improved smoke-producing mixture of calcium carbonate and pitch is placed in the 60 lower portion of the combustion chamber as at 20 to be acted upon by the burner 12. When the mixture 20 is acted upon by the burner 12 under a restricted supply of air through the openings 15, dense volumes of 65 smoke are produced which are delivered into the surrounding atmosphere through the pipe 11. During this operation the heat from the burner 12 raises the temperature of the mixture 20 and consequently causes 70 the $CaCO_3$ to be split up into calcium monoxide (CaO) and nascent carbon dioxide (CO_2), and the nascent carbon dioxide thus produced acts in a well known manner to partially smother or choke the combustion of 75 the pitch and to quickly produce large volumes of dense smoke.

While it has been found that a mixture of calcium carbonate and pitch are effective for the purposes of this invention, it is to be understood that the invention is not limited in its application to a mixture of these specific substances but might include the combination of any equivalent substances without departing from the spirit of the invention 85 or the scope of the appended claims.

Having thus fully described this invention, we claim:

1. The process of producing smoke which consists of enclosing a combustible material 90 and a material which when heated will retard the combustion of said combustible material, directing a flame upon said enclosed materials and mixing a restricted supply of air with the ignited material. 95

2. The process of producing smoke which consists of enclosing a combustible material and a material which when heated will retard the combustion of said combustible material, and subjecting said material to a continuously burning flame. 100

3. The process of producing smoke which consists of enclosing a combustible material, mixing a carbonate with said material and breaking up said carbonate by heat to produce nascent carbon dioxide. 105

4. The process of producing smoke which consists of enclosing a combustible material, mixing a carbonate with said material, subjecting said mixture to the heat of a flame 110

to break up said carbonate to produce nascent carbon dioxide and placing the burning mixture under the influence of a restricted amount of air.

5. The process of producing smoke which consists of enclosing a suitable quantity of pitch, mixing calcium carbonate with said pitch, subjecting the mixture to the heat of a flame to break up said calcium carbonate 10 to produce nascent carbon dioxide, and placing the burning mixture under the influence of a restricted amount of air.

6. The process of producing smoke which consists in enclosing a suitable quantity of 15 combustible material, mixing a combustion deterrent with said material, and subjecting the mixture to a continuously burning flame to cause a slow combustion of said com-

bustible material and the decomposition of said combustion deterrent under the influence of a restricted amount of oxygen.

7. The process of producing smoke which consists in mixing a combustible material, and a material which when heated will decompose and retard the combustion of said combustible material, and causing a slow combustion of said combustible material, and the heating of said second mentioned material in the presence of a restricted supply of oxygen, to cause decomposition of the second named material.

In witness whereof we have hereunto set our hands.

JOHN HAYS HAMMOND, JR., [L. S.]
HENRY L. F. BUSWELL. [L. S.]
